OPHTHALMIC MOUNTING

Louis L. Gagnon, Southbridge, Mass., assignor to
 American Optical Company, Southbridge,
 Mass., a voluntary association of Massachu-
 setts

Application January 3, 1938, Serial No. 182,934

7 Claims. (Cl. 88—47)

This invention relates to improvements in ophthalmic mountings and has particular reference to lens holding means of the type which is adapted to be yieldingly supported on the lenses.

One of the principal objects of the invention is to provide lens holding means of the above character with resilient means having a plurality of resilient sections which are positively supported with the major portions thereof held in spaced aligned relation with each other with substantially only the ends of one of said resilient sections engaging the other of said sections and with only the ends of the resilient section nearest the lens engaging the edge of the lens.

Another object of the invention is to provide means for holding said resilient sections in aligned superimposed relation with each other.

Another object is to provide improved means of assembling and attaching the resilient means to the lens holding means.

Another object is to provide improved means of forming resilient means of the above character wherein said resilient sections will be retained in sliding interlocked relation with each other and with the portion overlying the edge of the lens.

Another object is to provide resilient means of the above character with the various resilient sections thereof having different degrees of resiliency.

Other objects and advantages of the invention should become apparent from the following description taken in connection with the accompanying drawing. It is apparent that many changes may be made in the details of construction, and arrangement of parts shown and described without departing from the spirit of the invention as expressed in the accompanying claims. I, therefore, do not wish to be limited to the exact details of construction, and arrangement of parts shown and described as the preferred forms are given only by way of illustration.

Referring to the drawing:

Fig. I is a front elevation of an ophthalmic mounting embodying the invention.

Fig. II is a fragmentary sectional view of one form of lens strap or lens holding means embodying the invention.

Fig. III is a view similar to Fig. II of another form of lens strap embodying the invention.

Fig. IV is a view similar to Fig. III of another form of lens strap embodying the invention.

Fig. V is a side elevation, shown partially in section, of a modified form of attaching means

for securing the resilient means to the lens strap.

Fig. VI is a fragmentary perspective view of a modified form of the invention showing the parts disunited; and

Fig. VII is a view similar to Fig. III of another modified form of the invention.

Lens holding means or lens straps having resilient lens edge engaging means are not new in the art, but much difficulty has been encountered, in the past, in providing suitable means for securing the resilient means to the lens holding means so that the said resilient means will be properly supported and held with the various resilient sections thereof in desired aligned relation with each other.

It, therefore, is one of the primary objects of this invention to provide novel means and methods of forming and securing the resilient sections to the lens holding means whereby the said resilient sections will be retained in positive relation with the lens holding means and in proper aligned superimposed relation with each other during use.

Referring more particularly to the drawing wherein like characters of reference designate like parts throughout the several views, the device embodying the invention comprises broadly a pair of lenses 1 connected by a suitable bridge member 2 secured to said lenses by lens straps or lens holding means 3. Suitable temples 4 are also secured to the lenses 1 by means of the lens holding means or lens straps 5 and are adapted to cooperate with the bridge member 2 to hold the lenses in proper position before the eyes.

The lens straps 3 and 5 are adapted to be pivotally connected to the lenses, as shown at 6 and 7, and are resiliently limited in their pivotal movement by resilient means 8 and 9 which embody the invention.

The lens holding means 3, as shown in Fig. III, comprises a lens face engaging portion 10 pivotally connected at 7 to the lens 1 and a portion 11 which overlies the edge of the lens. The portion overlying the edge of the lens provides attaching means to which the resilient means 9 is secured by a suitable headed pin or the like.

12. The resilient means 9, in this particular instance, comprises two superimposed resilient sections 13 and 14 but it is to be understood that two or more resilient sections may be used as desired.

The pin 12 is provided with an intermediate shouldered portion 15 which functions as means for positively holding the resilient sections 13 and 14 in spaced relation with each other. The re-

silient section 14 is so cupped as to cause the ends 16 thereof to engage the outer surface of the resilient section 13 and the said resilient section 13 is so cupped as to cause its ends 17 to engage 5 the edge of the lens. In this particular instance the section 14 normally has a greater degree of cupping than the section 13. The pin 12 is provided with a reduced extension 18 which is fitted within a suitable opening formed in the portion 10 11 overlying the edge of the lens and may be secured therein by friction or by threading, soldering or welding the said extension 18 in said opening. The resilient section 13 is held against the shoulder portion 15 by heading over the end 15 19. This heading over may be performed either before or after the pin member 12 is secured to the portion 11 overlying the edge of the lens. In this particular instance the openings in the resilient means through which the reduced portions 20 of the pin member 12 extend, are preferably formed square or rectangular in shape with the said reduced portions similarly shaped to fit said openings so as to hold the resilient sections in proper aligned relation with each other during 25 use. It is particularly pointed out that the portion 11 overlying the edge of the lens is formed relatively short in the direction following the edge of the lens so as to enable a relatively free flexing of the resilient sections 13 and 14 throughout 30 the major portion of their lengths during use. When in secured position the shouldered portion 15 holds the resilient sections 13 and 14 in given spaced relation with each other and prevents any movement thereof longitudinally of the pin member 12 during use.

In Fig. IV there is shown the high position lens strap 5 which also has a portion 20 overlying a face of the lens and pivotally secured to said lens as illustrated at 6. The means for pivotally connecting the lens strap 3 or 5 to the lens may be of any of the commercially known solder locked or threaded types. The lens strap 5 also has a portion 21 overlying the edge of the lens and is provided on the upper side thereof with a projection 22 to which the resilient means 8 are secured by a pin member 23 generally similar in construction and function as the pin member 12. The pin member 23, like the pin member 12, is secured within a suitable opening formed in the projection 22 and is so positioned on the projection 22 as to provide an equal degree of flexing on either side of the pivotal connection 6. The resilient means in this instance also comprises two superimposed resilient sections 24 and 25 having characteristics generally similar to the resilient sections 13 and 14.

It is to be understood that the said sections 13 and 14 or 24 and 25, respectively, may be formed to different degrees of resiliency.

60 To provide free flexing of the lower ends of the resilient sections 24 and 25 the portion 21 overlying the edge of the lens is cut away as illustrated at 26.

In Fig. II there is illustrated a slightly modified form of the invention wherein a high position strap similar to 5 is illustrated, the only difference being that the portion 27 overlying the edge of the lens is not provided with an upward extension such as shown at 22 in Fig. IV. The 65 major portion of the attaching face 28, to which the resilient means 29 having generally the same characteristics as the resilient means 8 and 9 are secured, lies above a horizontal line 30 extending through the pivotal connection 31 to the 70 lens. The pin 32 in this particular instance has 75

the same characteristics and functions in the same manner as the pins 12 or 23.

In Fig. V there is shown a slight modification of pin member 32 which, instead of having a shouldered portion such as called for at 15, in Fig. III, the said pin member is provided with a suitable collar 34 which functions generally similar to the shouldered portion 15. In this particular instance the pin 32 is provided with an enlarged head 35 adjacent one end thereof and the main body portion of the main pin member is rectangular in shape as illustrated at 36. The collar 34 is provided with a rectangular opening which has a snug fit with the body portion of the pin member during use. A plurality of collars of varying lengths may be provided to hold the resilient sections in varied spaced relation with each other. A pin member similar to the pin 32 and its function is illustrated in Fig. VII wherein the resilient section 37 is secured between the head of the attaching means 38 and collar 39 and the resilient section 40 is held between the collar 39 and portion of the lens strap 41 overlying the edge of the lens. In this particular instance the resilient sections 37 and 40 are provided with longitudinal grooves 42 and 43. The resilient section 40 is provided with deflected ends 44 which are adapted to slidably engage the resilient section 37 within the longitudinal groove 42 and prevent disalignment of said sections during use. The portion 41 overlying the edge of the lens is also provided with projections 45 which slidably engage the resilient section 40 internally of the longitudinal groove 43 and tends to yieldingly support the said section 40 and simultaneously prevent twisting thereof sidewise on the connecting means 38 during use. The portion overlying the edge of the lens is shown as being provided with a curved supporting face 46 but it is to be understood that this face may be formed flat or to any practical shape desired. In Fig. VI there is shown another modified form of the invention where instead of forming longitudinal grooves which extend partially through the resilient sections such as shown at 42 and 43, the said resilient sections 47 and 48 are provided with longitudinal slots 49 and 50 in which the projections 51 and 52 are adapted to be slidably fitted. In this particular instance, the portion 53 which overlies the edge of the lens is provided with a rectangular pin member 54 which is adapted to be fitted within the rectangular openings 55 and 56 of the respective resilient sections 47 and 48 which are secured to said portion 53 overlying the edge of the lens by heading over the pin member 54. A spacing collar such as shown at 39 may or may not be used as desired and the resilient sections 47 and 48 may be provided with the same or different degrees of cupping.

It is to be understood that the constructions shown in Figs. VI and VII are to be used with a lens strap pivotally attached to the lens in a manner similar to the above described lens straps.

It may be desirable to use the resilient means 65 embodying the invention and the various modifications thereof with a lens strap having a single lens face engaging portion formed with a resilient section intermediate its end attached to the lens and the portion thereof overlying the 70 edge of the lens to permit flexing of said portion overlying the edge of the lens in a direction transversely to the plane of the lens simultaneous to the flexing of the resilient means engaging the 75 edge of the lens in the plane of said lens. In 75

the latter instance the resiliency of the various resilient portions will be carefully balanced so as to cause the lens holding means to normally assume a desired aligned relation with the lens.

5 It is to be understood that attaching means for the resilient sections of the type illustrated at 12 in Fig. III or at 38 in Fig. VII may be used with any of the above constructions.

From the foregoing description it will be seen 10 that simple, efficient and economical means have been provided for accomplishing all of the objects and advantages of the invention particularly that of providing resilient means having a plurality of resilient sections supported so that the 15 said sections engage each other and the edge of the lens only adjacent the ends of said sections and that novel means have been provided for holding the sections in positive spaced relation with each other and in positive aligned superimposed relation with each other during use.

Having described my invention, I claim:

1. Lens holding means for use with a lens comprising a portion adapted to overlie the edge of the lens and a portion adapted to overlie a face of the lens, said portion overlying the edge of the lens having a projection thereon, a plurality of resilient members each formed with a longitudinal groove in one face thereof, one of said resilient members being fitted to said portion overlying the edge of the lens with the projection on said portion fitting within the longitudinal groove of said resilient member and another resilient member being fitted to said last named resilient member with the ends of said last named resilient member fitting within the longitudinal groove thereof and means for securing said resilient members to said portion overlying the edge of the lens in this relation.

2. Lens holding means for use with a lens comprising a portion adapted to overlie the edge of the lens and a portion adapted to overlie a face of the lens, said portion overlying the edge of the lens having a projection thereon, a plurality of resilient members each formed with a longitudinal groove in one face thereof, one of said resilient members being fitted to said portion overlying the edge of the lens with the projection on said portion fitting within the longitudinal groove of said resilient member and another resilient member being fitted to said last named resilient member with the ends of said last named resilient member fitting within the longitudinal groove thereof, means for securing said resilient members to said portion overlying the edge of the lens in this relation and means for holding said resilient members in positive spaced relation with each other intermediate their ends.

3. Lens holding means for use with a lens comprising a portion adapted to overlie the edge of the lens and a portion adapted to overlie a face of the lens, said portion overlying the edge of the lens having a projection thereon, a plurality of resilient members each formed with a longitudinal groove in one face thereof, one of said resilient members being fitted to said portion overlying the edge of the lens with the projection on said portion fitting within the longitudinal groove of said resilient member and another resilient member being fitted to said last named resilient member with the ends of said last named resilient member fitting within the longitudinal groove thereof, means for securing said resilient members to said portion overlying the edge of the lens in this relation and sleeve means positioned 70 on said securing means between said resilient

members for holding the said resilient members in positive spaced relation with each other intermediate the ends thereof.

4. Lens holding means for use with a lens comprising a portion adapted to overlie the edge of the lens and a portion adapted to overlie a face of the lens, said portion overlying the edge of the lens having a projection thereon, a plurality of resilient members each formed with guide means on one face thereof, means separate of said projection for securing said resilient members to said portion adapted to overlie the edge of the lens, one of said resilient members attached to said portion overlying the edge of the lens having the projection on said portion fitting said guide means on said resilient member and another of said resilient members when in secured relation with said portion adapted to overlie the edge of the lens and when assembled with said lens being fitted to said last named resilient member with the ends of said last named resilient member formed to fit the guide means thereof.

5. Lens holding means for use with a lens comprising a portion adapted to overlie the edge of the lens and a portion adapted to overlie a face of the lens, said portion overlying the edge of the lens having a projection thereon, a plurality of resilient members each formed with guide means on one face thereof, means separate of said projection for securing said resilient members to said portion adapted to overlie the edge of the lens, one of said resilient members attached to said portion overlying the edge of the lens having the projection on said portion fitting said guide means on said resilient member and another of said resilient members when in secured relation with said portion adapted to overlie the edge of the lens and when assembled with said lens being fitted to said last named resilient member with the ends of said last named resilient member formed to fit the guide means thereof, and a spacer member between said resilient members for holding the intermediate portions thereof in positive spaced relation with each other.

6. An ophthalmic mounting comprising a pair of lenses, and lens holding means for connecting the associated parts of the mounting with said lenses, said lens holding means comprising a portion overlying a face of the lens and a portion overlying the edge of the lens having an attachment seat thereon, a plurality of resilient members of varying lengths secured to said attachment seat of the portion overlying the edge of the lens with means between the intermediate portions of said resilient members for positively spacing said intermediate portions relative to each other and with the ends of said resilient members being free to flex independently of each other and with one of said resilient members having a guide surface on one face thereof engaged by another of said resilient members with the ends of said last named resilient member formed to fit and have a sliding contact with said guide surface of said first resilient member and with said first resilient member engaging the adjacent edge of the lens for free sliding contact therewith, the said means for securing said resilient members to said attachment seat being such as to rigidly support said resilient members in connected relation with said attachment seat and in positive spaced relation with each other with the cupping of one of said resilient members

being greater than the other thereof which engages the edge of the lens.

7. In an ophthalmic mounting a pair of lenses, a portion overlying the edge of the lens and a portion overlying a face of the lens, said portion overlying the edge of the lens having a projection thereon, a plurality of resilient members each formed with guide means on one face thereof, means separate of said projection for securing said resilient members to said portion adapted to overlie the edge of the lens, one of said re-

silient members attached to said portion overlying the edge of the lens having the projection on said portion fitting said guide means on said resilient member and another of said resilient members when in secured relation with said portion adapted to overlie the edge of the lens and when assembled with said lens being fitted to said last named resilient member with the ends of said last named resilient member formed to fit the guide means thereof. 10

LOUIS L. GAGNON.
